UNITED STATES PATENT OFFICE.

DAVID REISZ, OF CLEVELAND, OHIO.

GAME APPARATUS.

Application filed February 12, 1923. Serial No. 618,634.

To all whom it may concern:

Be it known that I, DAVID REISZ, a citizen of the United States, and a resident of Cleveland, in the county of Cuyahoga and State of Ohio, have invented a new and Improved Game Apparatus, of which the following is a full, clear, and exact description.

This invention relates to improvements in game apparatus and more particularly to a combined checker and chess game apparatus embodying modifications and improvements having particular relation to the same art as disclosed in my pending application for game apparatus, filed July 17, 1922, and given Serial No. 575,532.

An object of the invention is to provide a game apparatus in which the game pieces are stored in a frame or frames which together with a backing sheet constitute a receptacle or receptacles having rigid relation to each other, and accommodating a complete set of game pieces which are entirely exposed when the apparatus is open and which are completely confined and securely housed when the apparatus is closed.

A further object is to provide a game apparatus of the character stated, which when folded will be relatively flat and compact so as to occupy but small space in a traveling bag or in the pocket of the user.

A further object is to provide a game apparatus, which will be ornamental and attractive in appearance, which will be complete, and which can be manufactured and sold at a reasonably low price.

A further object is to provide a game apparatus of the character stated, in which the game pieces are supported in a frame or frames of proper size and shape to nicely accommodate the game pieces, and maintain all of the game pieces visible when the game apparatus is ready for play, so that they can be easily reached for removal or replacement from their containers.

With these and other objects in view, the invention consists in certain novel features of construction and combinations, and arrangement of parts, as will be more fully hereinafter described and pointed out in the claims.

In the accompanying drawings—

Figure 1 is a plan view illustrating one

form of my improved game apparatus in open position ready for play. 55

Figure 2 is a view of the same game apparatus when folded, the view being on a reduced scale.

Figure 3 is a view in transverse section on the line 3—3, of Figure 2. 60

Figures 4, 5; 6, 7; and 8, 9; are views in longitudinal and transverse sections respectively illustrating various modifications.

Figures 10, 11 12, 13 and 14, are views illustrating other modifications. 65

Referring particularly to Figures 1, 2 and 3, 1 represents a sheet which may be made up of any number of thicknesses of material, and which is to all intents and purposes rigid and inflexible, except at certain fold lines, or fold sections, indicated by the reference numerals 2, 3 and 4. 70

It will be noted that these fold lines, or sections, extend transversely of the sheet 1, and that there are no fold lines or sections longitudinally of the sheet. On the sheet 1, between the fold lines or sections 2 and 3, a pair of rigid frames 5 and 6 are fixedly secured and located end to end. 75

These frames 5 and 6 constitute receptacles or containers for game pieces 7, and these game pieces 7 are preferably combined checker and chess game pieces, such as disclosed in my former application above referred to. 80

Each frame 5 and 6 is of the proper depth to accommodate the game pieces, and is of the proper area to accommodate all of the game pieces of one set so that in storing the game pieces, all the game pieces of one set are stored in one frame, and all the game pieces of the other set in the other frame. 85

The sheet 1, between the fold 3 and one end of the sheet, constitutes a game board 8, which is preferably the ordinary checker or chess game board; this game board having but a single fold 4 centrally thereof. 90

The end section 9 of sheet 1 constitutes a covering flap, and is provided with snap button members 10 adapted to engage corresponding snap button members on the back of the sheet 1 when the latter is in folded position, as will be explained. 100

Figure 1 shows the game apparatus in position for play, and it will be noted that when in such position all of the game pieces 105

are exposed and can be easily removed and replaced from their frames 5 and 6.

When it is desired to fold the game apparatus, the game pieces 7 are located in their proper frames 5 and 6, and sheet 1 is folded first on the fold line 4, and then on the fold line 3 to bring the game board section of the sheet flat upon the frames 5 and 6 and cover the game pieces 7, as clearly shown in Figure 3. The flap 9 is then folded over and secured by its snap button members 10 so that the apparatus will have very much the appearance of a pocketbook or billfold, and will be relatively thin and occupy but small space in storage or shipment.

In Figures 4 and 5 I illustrate a modification in which I employ a separate game board 11, the backing sheet 12 corresponding to the sheet 1 of Figures 1, 2 and 3, constituting solely a backing sheet and covering medium, and providing an upwardly projecting flange 13 extending above the frames 5 and 6, and providing ample space for the accommodation of the folded game board 11.

One end of the sheet 12 is folded over the game board as shown at 14, and the other end of the sheet constitutes a covering flap

30 15 secured to the section 14 by snap button members 16, so that in outward appearance, this form of my game apparatus is similar to the form shown in Figures 1, 2 and 3, when folded.

35 With this modification shown in Figures 4 and 5, the folded game board constitutes a direct cover for the game pieces 7, and serves to hold them in their frames when the apparatus is folded.

40 The modification shown in Figures 6 and 7 embodies the same idea of a separate folded game board 11, such as disclosed in Figures 4 and 5, but the covering and backing sheet 15 is differently formed in that 45 it extends around one edge of the frames 5 and 6, as shown at 16, and the other end of the covering sheet entirely incloses the game board and pieces, and has a relatively thin flange or tongue 17 secured to the section 16 by snap buttons 18.

50 In the modification shown in Figures 8 and 9, the same idea of a separate folded game board 11 is carried out, but in this form of game apparatus the frames 5 and 6 are secured within a box like container 19 and a flanged cover 20 incloses the same.

55 In all of the forms shown in Figures 4, 5; 6, 7; and 8, 9, the idea of an upwardly projecting flange extending above the frames 5 and 6 to provide a space for the folding game board 11 is utilized.

60 In Figures 10, 11 and 12 I illustrate another form of my invention in which I provide a single frame 21 accommodating thirty game pieces 7, the game pieces being

arranged in three rows of ten game pieces each, with the respective sets at the different ends of the frame.

Covering flaps 22 and 23 are adapted to be folded over the frame and inclose the 70 game board 11.

In Figures 13 and 14, I illustrate another modification in which a single frame 21 is employed, but a partition strip 24 is secured in notches 25 in the sides of the frame 75 and separates the frame into two compartments for the game pieces 7 of the different sets.

This form of single frame may be preferred over the double frame idea and I do not wish to be limited to the exact manner of constructing, shaping or forming the frame, but desire to cover broadly the idea of a frame for accommodating the game pieces in sets, either with or without a partition and in combination with a gameboard or cover which fits over the frame and confines the game pieces therein. As it is to be noted that the game pieces are of substantially the same depth as the frame and that when covered they are maintained in the frames, and when uncovered are exposed and are in convenient reach and arrangement for positioning on the board.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

I claim:

1. A game apparatus, comprising a backing sheet, a framing mechanism secured on the face of the backing sheet, said framing mechanism adapted to house therein game pieces contiguously with their faces fully exposed in the manner the game pieces are to be laid on a board when playing, said game pieces forming a single layer, a flap hingedly connected to the framing mechanism and backing sheet, and means for securing the flap upon the framing mechanism. 105

2. A game apparatus, comprising a backing sheet, a framing mechanism secured on the face of the backing sheet, said framing mechanism adapted to house therein game pieces contiguously with their faces fully exposed in the manner the game pieces are to be laid when playing, said game pieces forming a single layer, a foldable game board of proper size and shape when folded to fit on the framing mechanism and the game pieces, and means for enclosing the game board and holding it on the framing mechanism and the game pieces. 110

3. A game apparatus, comprising a backing sheet, a pair of rigid frames located end to end and fixed to the backing sheet, said 130

frames having rigid relation to the sheet and to each other, and of proper size and shape to accommodate in each frame a complete set of game pieces, and covering means 5 for the frames and game pieces.

4. A game apparatus, comprising a backing sheet, a pair of rigid frames located end to end and fixed to the backing sheet, said frames having rigid relation to the sheet 10 and to each other, and of proper size and shape to accommodate in each frame a complete set of game pieces, one section of the backing sheet adapted to be positioned over the frame and game pieces, and a covering 15 flap secured thereto.

5. A game apparatus, comprising a backing sheet, a pair of rigid frames located end to end and fixed to the backing sheet, said frames having rigid relation to the sheet 20 and to each other, and of proper size and shape to accommodate in each frame a complete set of game pieces, one section of the backing sheet adapted to be positioned over the frames and game pieces, flanges on the 25 backing sheet projecting above the frames, a folded game board located upon the frames within the flanges and constituting a cover for the game pieces, and means for inclosing the game board and holding it on the 30 frames and game pieces.

6. A game apparatus, comprising a backing sheet, a pair of rigid frames located end to end and fixed to the backing sheet, said frames having rigid relation to the sheet 35 and to each other, and of proper size and shape to accommodate in each frame a complete set of game pieces, one section of the backing sheet adapted to be positioned over the frames and game pieces, flanges on the 40 backing sheet projecting above the frames, a folded game board located upon the

frames within the flanges and constituting a cover for the game pieces, means for inclosing the game board and holding it on the frames and game pieces, said last mentioned means embodying sections of the backing sheet folded upon the game board, and securing means connecting said sections. 45

7. A game apparatus, comprising a backing sheet, a frame thereon adapted to contain flat game pieces placed contiguously in the manner the game pieces are to be laid on the game board when playing, said game pieces forming a single layer, and the ends of said backing sheet adapted to be positioned over and cover the frame and game 55 pieces.

8. A game apparatus, comprising a backing sheet, framing mechanism fixed to the backing sheet and having rigid relation 60 thereto and adapted to contain flat game pieces, said game pieces placed contiguously in the manner the game pieces are to be laid on the game board when playing, said game pieces forming a single layer, and said backing sheet constituting a covering means for the framing mechanism and the game pieces. 65

9. A game apparatus, comprising a foldable game board, framing devices at one end 70 of the game board and adapted to contain sets of game pieces, said game board being foldable upon itself and upon the framing devices and when folded of substantially the same area as the framing devices whereby 75 the game board constitutes a cover for the framing devices and the game pieces to hold the game pieces in the framing devices, and means for holding the game board in this folded closing position.

DAVID REISZ.
